(57) **CLAIM**

The ornamental design for a combination dispenser-container, as shown and described.

DESCRIPTION

FIG. 1 is a top, front, and right side perspective view of a combination dispenser-container showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken-line showing of a pump in the views is for illustrative purposes only and forms no part of the claimed design.
